UNITED STATES PATENT OFFICE

GEORGE H. NIEDERST, OF CHICAGO, ILLINOIS

DESIGN FOR A RADIATOR CAP

Application filed May 19, 1930. Serial No. 35,685. Term of patent 3½ years.

To all whom it may concern:

Be it known that I, GEORGE H. NIEDERST, a citizen of the United States, residing at Chicago, in the county of Cook and State of Illinois, have invented a new, original, and ornamental Design for a Radiator Cap, of which the following is a specification, reference being had to the accompanying drawing, forming a part thereof.

Fig. 1 is a front perspective view of a radiator cap, showing my new design; and
Fig. 2 is a top plan view of the same.

I claim:

The ornamental design for a radiator cap as shown.

GEORGE H. NIEDERST.
